M. H. Holmes.

Inventor:
 David L. Winters,
 by Robert Burns
 Attorney

UNITED STATES PATENT OFFICE.

DAVID L. WINTERS, OF CHICAGO, ILLINOIS.

RATCHET-WRENCH.

SPECIFICATION forming part of Letters Patent No. 736,047, dated August 11, 1903.

Application filed April 22, 1903. Serial No. 153,739. (No model.)

To all whom it may concern:

Be it known that I, DAVID L. WINTERS, a citizen of the United States of America, and a resident of Chicago, in the county of Cook and State of Illinois, have invented certain new and useful Improvements in Ratchet-Wrenches, of which the following is a specification.

The present invention relates to ratchet-wrenches, and has for its object to provide a simple and efficient construction of parts, whereby the usual number of parts is reduced and simplified and with which a readily-reversible nature is imparted to the wrench, all as will hereinafter more fully appear and be more particularly pointed out in the claim.

In the accompanying drawings, illustrative of the present invention, Figure 1 is a sectional elevation at line $x-x$, Fig. 2, of an ordinary ratchet-wrench embodying the present invention. Fig. 2 is a sectional elevation at line $x'-x'$ of Fig. 1. Fig. 3 is a side elevation of the wrench-chuck detached.

Similar numerals of reference indicate like parts in the different views.

Referring to the drawings, 1 represents the operating head or hub of the wrench, formed with a transverse cylindrical bearing-orifice 2 for the trunnion portion of the wrench-chuck, hereinafter described. Such head is also formed with a guide bore or recess 3, connecting with the bearing-orifice 2 aforesaid and adapted to hold the hereinafter-described spring dog or detent of the wrench.

4 is the operating handle bar or lever of the wrench, which will usually form an integral part of the wrench-head 1, but which, if desired, may be a separate member removably connected to said head, as usual in the present type of wrenches.

5 is a sliding dog or detent moving in the guide-recess 3 aforesaid and having the usual pointed end for engagement with the circularly-arranged ratchet-detents of the wrench-chuck.

6 is a spiral spring arranged in the recess 3 and having bearing against the sliding dog 5 and adapted to force the same into oper-

ative engagement with the ratchet-detents of the chuck-shank.

7 is a cross-pin attached to the sliding dog 5 and moving in elongated slots 8 in the sides of the wrench-head 1 to limit the extent of the sliding movement of the said dog or detent and to afford means for retracting the dog.

9 is the head portion of the wrench-chuck, formed with a receiving-recess 10 of any usual and required form, which adapts the same for operative engagement with a nut or other article to be rotated.

11 is a cylindrical extension or shank on the head portion 9 of the chuck, fitting the cylindrical bearing-orifice 2 of the chuck-head to form the trunnion upon which said head is oscillated.

12 represents a circularly-arranged series of ratchet-detents formed by notches or recesses in the periphery of the trunnion 11 and adapted for operative engagement by the spring-dog 5 aforesaid.

13 is an annular recess formed in the periphery of the trunnion 11 and having a length equal to that of the ratchet-detents 12 and that of the dog 5, the arrangement being such that the annular run 14, formed at the rear end of the trunnion by such annular recess, is adapted to have bearing against the side of the dog 5 to maintain the wrench parts in proper relative position and prevent longitudinal disengagement of the same during use. With the described construction the simple operation of pushing the spring-dog 5 up by hand to a retracted position in its guide-recess 3 will permit of a ready longitudinal disengagement of the wrench parts and a subsequent reassemblage of the same in an operation to effect a reversal of the wrench-chuck from a right-hand to a left-hand position, and vice versa.

Having thus fully described my said invention, what I claim as new, and desire to secure by Letters Patent, is—

In a ratchet-wrench, the combination of a wrench-head formed with a transverse bore, a wrench-chuck formed with a trunnion ex-

tension fitting the transverse bore of the operating-head, and adapted for ready longitudinal detachment therefrom, said trunnion being formed with a circular series of ratchet-
5 detents and with annular recess in its periphery, and a spring-dog arranged in the wrench-head and adapted for operative engagement with the ratchet - detents aforesaid and for lateral holding engagement with the annular

recess aforesaid to prevent longitudinal dis- 10 engagement of the chuck from the wrench-head, substantially as set forth.

Signed at Chicago, Illinois, this 17th day of April, 1903.

DAVID L. WINTERS.

Witnesses:

ROBERT BURNS,
M. H. HOLMES.
